UNITED STATES PATENT OFFICE.

ELMER P. SAWTELLE, OF BOSTON, MASSACHUSETTS, ASSIGNOR OF ONE-HALF TO CHARLES E. GETCHELL, OF BOSTON, MASSACHUSETTS.

NON-REFILLABLE BOTTLE.

SPECIFICATION forming part of Letters Patent No. 715,877, dated December 16, 1902.

Application filed November 18, 1901. Serial No. 82,099. (No model.)

To all whom it may concern:

Be it known that I, ELMER P. SAWTELLE, a citizen of the United States, residing in Boston, in the county of Suffolk and State of Massachusetts, have invented an Improvement in Non-Refillable Bottles, of which the following description, in connection with the accompanying drawings, is a specification, like letters on the drawings representing like parts.

This invention relates to a bottle or like receptacle, and has for its object to provide one which cannot be refilled. For this purpose I employ a light and a heavy ball and a cone-shaped spiral having its convolutions separated to form lateral passages for the liquid contents of the bottle, but which overlap one another, so as to effectively close the bottle against the passage into the bottle of a fine wire or other device, and which is provided with a top piece or disk covering the opening at the apex of the cone for the same purpose. The light ball constitutes a valve and coöperates with a conical seat, which may be formed in the neck of the bottle. The heavy ball forms a weight which coöperates with the valve to seat the same, as will be described. The conical spiral may be made of glass or other suitable material and may be secured in the neck of the bottle against withdrawal in any suitable manner. These and other features of this invention will be pointed out in the claims at the end of this specification.

Figure 1 is an elevation and section of a sufficient portion of a bottle embodying this invention to enable it to be understood; and Figs. 2 and 3, details to be referred to, Fig. 3 being an inverted view of Fig. 2.

The bottle *a*, provided with the neck *b*, may be of any suitable construction or configuration and is herein shown as provided with a contracted portion in the neck *b* to form a conical port or opening *c*, with which coöperates a light ball *d*, of cork or other suitable material, which in practice constitutes a valve for the bottle. The cork ball *d* has coöperating with it a heavy ball *e*, of glass or other suitable material, which serves to keep the ball *d* to its seat when the bottle occupies an upright or an inclined position.

Within the neck *b* of the bottle and beyond the port or opening *c* a suitable dis-

tance is located a conical spiral *f*, which I prefer to designate as an "obstracter," inasmuch as its function is to prevent the balls 55 passing out of the neck when the bottle is inverted or tipped in the act of pouring and also and more particularly to prevent the passage of a fine wire or other device into the bottle so as to reach the valve or to be inserted into the valve-opening when the bottle is in its inclined or inverted position. The conical spiral obstracter, while effectively preventing the entrance of an extraneous solid body into the bottle, does not offer any material obstruction to the passage of the liquid out of the bottle, inasmuch as its convolutions are separated a sufficient distance to form lateral ports or passages *g*, through which the liquor or other fluid in the bottle 70 may pass when it is desired to pour the same out of the bottle. The conical spiral obstracter may be made of glass or other suitable material and may and preferably will have its convolutions of suitable width to 75 overlap one another, as represented by dotted lines, Figs. 2 and 3, and the bottom of the said obstracter may have attached to it cross-bars *h*, which prevent the ball *e* from closing the opening in the bottom of the obstracter 80 when the bottle is tipped in the act of pouring. The conical spiral obstracter is provided with a top piece or disk *k*, which covers the opening at the apex of the cone and prevents the insertion of a fine wire down 85 through the center of the cone. The obstracter may be secured in the neck of the bottle against removal without destroying the same in any suitable manner—as, for instance, by means of a bead *i*, formed in the neck of the 90 bottle after the obstracter is placed in position, which bead is indicated by dotted lines, Fig. 1, or by means of a suitable cement or in any other suitable manner.

I may prefer to employ the conical spiral 95 obstracter with a ball-valve and with a ball-shaped weight; but I do not desire to limit my invention in this respect, as it is evident the said obstracter may be used with other forms of valves and weights coöperating therewith.

I claim—

1. The combination with a bottle or like receptacle, of a valve to close said bottle, and

a conical spiral obstrucer located in the neck of the bottle and having its convolutions separated to form lateral passages and provided with a top piece or disk integral with 5 said convolutions and covering the opening at the apex of the cone, substantially as described.

2. The combination with a bottle or like receptacle, of a valve to close said bottle, and 10 a conical spiral obstrucer located in the neck of the bottle and having its convolutions overlapping one another and separated to form lateral passages and provided with a top piece or disk attached to the convolutions 15 and covering the opening at the apex of the cone, substantially as described.

3. The combination with a bottle or like receptacle, of a light ball located in the neck

of the bottle and forming a valve, a heavier ball coöperating with said light ball, and a 20 conical spiral obstrucer located in the neck of the bottle above said balls and having its convolutions overlapping one another and separated to form lateral passages and provided with a top piece or disk integral with 25 said convolutions and covering the opening at the apex of the cone, substantially as described.

In testimony whereof I have signed my name to this specification in the presence of 30 two subscribing witnesses.

ELMER P. SAWTELLE.
